UNITED STATES PATENT OFFICE

2,523,257

ROTATABLE TARGET FOR PIN BALL GAME APPARATUS

Jack Firestone, Brooklyn, N. Y., assignor of eighty per cent to Supreme Enterprise, Incorporated, Brooklyn, N. Y., a corporation of New York

Application May 16, 1947, Serial No. 748,566

3 Claims. (Cl. 273—127)

1

This invention relates to improvements in pin ball game apparatus of the type in which a plurality of targets are mounted on the periphery of a revolving disk so as to successively move across an alley downwardly to and upwardly from a position where the same may be struck by a ball rolled down the alley, in which the targets are hinged to be swung rearwardly and upwardly from a vertical set position to a substantially horizontal inoperative position when struck by a ball, and in which each target is held in either position by the action of a tension spring which is movable to opposite sides of the hinging point of the target.

The present invention has particular reference to an improved electrical means for registering the scores made in playing a game by use of an apparatus of the above type.

In accordance with the present invention, the targets are preferably arranged in a plurality of sets, with a plurality of targets in each set that progressively and similarly increase in scoring value. An electrical contact is provided on the back of each target, and the contacts of the targets of each set are arranged outwardly of and at progressively increased distances from the hinging points of said targets. A plurality of fixed contact elements are mounted in back of the revolving disk for co-action with the contacts of rearwardly swung or struck targets so as to close the circuit of and thereby energize an electrical score registering device. These fixed contact elements progressively extend to or are progressively located at lesser distances from the revolving disk so that only one of the same will be engaged by the contact of the target of each set having the lowest scoring value for thereby effecting only a single energization of the score registering device, so that two of the same will be engaged by the contact of the target of each set having the next higher scoring value for effecting two energizations of the score registering device, and so on. The score registering device is of a conventional re-settable type adapted to register a predetermined number of points upon each energization thereof, so that the scores registered will correspond in value to the values of the rearwardly swung or struck targets. The fixed contacts are mounted on the periphery of a ring having a peripheral cam arranged to coact with the contacts of the targets for resetting the latter to their vertical operative positions after their scoring values have been registered and before they return to the position for being struck by a ball rolled down the alley.

The exact nature of the present invention will become apparent from the following description

2

when considered in connection with the accompanying drawings, in which:

Figure 1 is a perspective view of a bowling alley equipped with a target and score registering device embodying the present invention.

Figure 2 is an enlarged view, partly in elevation and partly in the central vertical section on line 2—2 of Figure 3, of the target device shown in Figure 1.

10 Figure 3 is a vertical section taken on line 3—3 of Figure 2, with one of the targets in rearwardly and upwardly swung position.

Figure 4 is a rear perspective view of one of the targets.

15 Figure 5 is an enlarged perspective view of one of the brackets which are fixed to the periphery of the revolving disk and to which the targets are hinged.

Figure 6 is a vertical transverse section taken on line 6—6 of Figure 2.

20 Figure 7 is a wiring diagram showing the manner in which the contacts of the targets co-act with the fixed contacts for energizing the score registering device.

25 Referring in detail to the drawings, 5 indicates a bowling alley having a ball return 6 at one side thereof and a score registering device 7 at the other side of that end of the alley where the bowler remains in playing the game. A suitable backstop 8 is provided at the other end of the alley 5 and houses a target device which includes a plurality of targets 9 intended to be struck by balls 10 rolled down the alley 5.

The target device includes a revolving disk 11 having a circular series of the targets 9 mounted on the periphery thereof so as to successively move across the alley 5 downwardly to and upwardly from a position where the same may be struck by a ball 10 rolled down the alley. The disk 11 is secured on a horizontal shaft 12 driven by an electric motor 13 mounted by suitable bracket means 14 upon the rear wall 15 of the backstop 8.

40 The targets 9 are hinged to be swung rearwardly and upwardly from a vertical "set" or operative position as shown by full lines in Figure 2 to a substantially horizontal inoperative position, as shown by dotted lines at the bottom of Figure 2, when struck by a ball. For this purpose, each target 9, which may be in the nature of an

50 elongated plate shaped similar to a bowling pin, is provided at the back with a rearwardly projecting hinge member 16 pivoted at 17 to a second hinge member 18 secured on the periphery of disk 11. The arrangement is such that the inner end of target 9 will abut the margin of disk 11 to limit swinging of the target outwardly and forwardly to the vertical operative position. A

helical tension spring 19 connects each target with the disk 11 so that said spring is movable to opposite sides of the hinging point 17 of the target for holding the latter in either position thereof. The targets are preferably arranged in a plurality of sets as shown, with a plurality of targets in each set that progressively and similarly increase in scoring value as indicated by the scoring numerals 20 thereon. A rearwardly projecting electrical contact pin 21 is provided on the back of each target, and the contact pins 21 of the targets of each set are arranged outwardly of and at progressively increased distances from the hinging points 17 of said targets. The contact pins 21 of all of the targets are connected by flexible conductors 22 with a conductor ring 23 secured on the back of the disk 11 concentric with shaft 12. The conductor ring 23 carries a brush 24 that engages a peripheral collector ring 25 of a stationary disk 26 disposed concentric with shaft 12 behind disk 11. The stationary disk 26 is fixed to a supporting ring 27 carried by the bracket means 14 directly behind said disk 26. Secured on supporting ring 27 is an insulating band 28 having a plurality of spaced transverse fixed contact elements 29 embedded in the outer surface thereof. The contact elements 29 are connected by a conductor 30, and they progressively extend to or are progressively located at lesser distances from the revolving disk 11 so that only one of the same will be engaged by the contact of the target 9 of each set having the lowest scoring value, for thereby effecting only a single energization of the score registering device 7, so that two of the same will be engaged by the contact of the target of each set having the next higher scoring value, for effecting two energizations of the score registering device, and so on. The score registering device 7 is of a conventional resettable type adapted to register a predetermined number of points upon each energization thereof, so that the scores registered will correspond in value to the values of the rearwardly swung or struck targets. One wire 31 of a two-wire conductor cord 32 is connected to the collector ring 25, and the other wire 33 of conductor cord 32 is connected to the conductor 30 which connects the contact elements 29. Wire 31 extends to one side of a source of electricity 34, whose other side is connected to one side of the register 7. The wire 33 connects to the other side of register 7, and it will be seen that the circuit of register 7 will be closed each time a contact pin 21 engages a contact 29, for energizing and causing operation of said register 7.

It will be noted that the contacts 29 are arranged on one side portion of band 28 so as to be engaged by the contact pins 21 of struck targets 9 as they move upwardly at this side portion of band 28.

At the top and beyond the contacts 29, the band 28 is provided with a cam 35 arranged to co-act with the contacts 21 of the struck targets for re-setting the latter to their vertical operative positions after their scoring values have been registered and before they return to the position for being struck by a ball rolled down the alley 5. A suitable switch 36 may be provided for manually opening or closing the circuit of register 7 aside from the controlling action of the contact pins 21 and contact elements 29 on said circuit. Also, a manually operable switch 37 may be mounted on the registering device 7 for controlling the operation of motor 13.

In operation, the motor 13 is placed in operation by closing switch 37, thereby causing rotation of disk 11 in a counter-clockwise direction as viewed in Figures 1 and 3. As the targets 9 move downwardly into proximity to the surface of alley 5, they reach a position wherein the same may be struck by a ball 10 rolled down the alley. When a target is struck by a ball, it is caused to swing rearwardly and upwardly to the horizontal dotted line position of Figure 2, being maintained in such position by the associated spring 19 which has been moved rearwardly past the hinging point 17 of the target in question. When the target is so swung, its contact pin 21 engages the outer surface of band 28 and, upon continued rotation of disk 11, said contact pin 21 will move across the contact element or elements 29 arranged in the path thereof. Each time the contact pin 21 engages a contact element 29, the circuit of register 7 is closed so that the register registers a predetermined number of points. The contact pin of the struck target then rides over cam 35 so that the latter swings the target upwardly and forwardly for resetting the same in a vertical operative position, the target being retained in the latter position by its associated spring 19 due to passage of the latter forwardly past the hinging point 17 of the target.

From the foregoing description, it is believed that the construction, operation and advantages of the present invention will be readily understood and appreciated by those skilled in the art. Modifications and changes in details of construction are contemplated, such as fall within the scope of the invention as claimed.

What I claim is:

1. In a pin ball game apparatus, a vertical motor-driven revolving disk, a plurality of targets hingedly mounted on the periphery of said disk for being swung rearwardly and upwardly from a vertical set position to a substantially horizontal inoperative position, a tension spring connected between each target and the disk so as to be mounted for movement to opposite sides of the hinging point of said target for holding the latter in either of said positions, and a stationary cam arranged adjacent and behind said disk and co-acting with the rearwardly swung targets for resetting them in a vertical operative position upon continued rotation of said disk.
2. In a pin ball game apparatus, a vertical motor-driven revolving disk, a plurality of targets hingedly mounted on the periphery of said disk for being swung rearwardly and upwardly from a vertical set position to a substantially horizontal inoperative position, a tension spring connected between each target and the disk so as to be mounted for movement to opposite sides of the hinging point of said target for holding the latter in either of said positions, and a stationary cam arranged adjacent and behind said disk co-acting with the rearwardly swung targets for resetting them in a vertical operative position upon continued rotation of said disk, and cam-engaging pins projecting rearwardly from said targets outwardly of the hinging points of the latter.
3. In a pin ball game apparatus, a vertical motor-driven revolving disk, a plurality of targets hingedly mounted on the periphery of said disk for being swung rearwardly and upwardly from a vertical set position to a substantially horizontal inoperative position, a tension spring connected between each target and the disk so as to be

mounted for movement to opposite sides of the hinging point of said target for holding the latter in either of said positions, a stationary cam arranged adjacent and behind said disk and co-acting with the rearwardly swung targets for resetting them in a vertical operative position upon continued rotation of said disk, cam-engaging pins projecting rearwardly from said targets outwardly of the hinging points of the latter, a stationary supporting ring concentric with the axis of said disk, and a band on said supporting ring said cam being carried by said band.

JACK FIRESTONE.
